METHOD OF FORMING GRAB IRONS

William F. Cremeen, Toledo, Ohio

Application June 17, 1943, Serial No. 491,211

3 Claims. (Cl. 29—148)

My invention relates to a method of forming grab irons, handholds or other similar members having flattened feet portions by which they may be attached to a suitable support.

The prevailing method of forming a grab iron requires cutting a straight bar or rod to a required length, upsetting material at each end of the bar, forging feet portions from the upset material and then punching a hole in each foot portion and bending the feet to make the required design of grab iron.

The principal object of this invention is to eliminate one of the two upsetting or forging operations in the method now in general use so as to reduce the total number of operations required to form a grab iron and otherwise simplify the process. This in brief is accomplished by forming the rod or bar with curved end portions of such shape that by applying force to them in a direction longitudinally of the rod they may be upset in a single operation into flattened portions having the contour of the feet of the grab iron.

According to my improved method a bar or rod which is adapted to be formed with a succession of bowed portions is moved a predetermined distance in the direction of its length after the formation of each bowed portion, and as each new bowed portion is formed a previously formed bowed portion is simultaneously cut at its center so that each severed section of the rod is provided with curved end portions. Each curved end portion of each severed section of the rod is then placed within a die provided with a cavity which in cross section corresponds to the contour of the feet with which the grab iron is to be formed and force is then applied to each end of the rod in a direction longitudinally of the axis thereof to upset the curved end portion and form the rod with a flattened portion arranged substantially normal with the axis of the rod having the desired contour. The ends of the rod are restrained from moving laterally of the die cavity during the upsetting of the curved portions so that the metal of those portions will spread substantially uniformly within the cavity, and as the upsetting operation is being concluded an indentation is formed in the flattened portions which serves to center means which is subsequently employed for punching holes therein. Thereafter the rod is bent to dispose the flattened portions in the desired relation with respect thereto.

The various steps of the improved method are

illustrated in the accompanying drawings wherein

Figure 1 shows a pair of die members in closed position to form a bowed portion in a rod or bar and also shows a pair of shear blades cutting a bowed portion which has been previously formed in the rod.

Figure 2 is a side elevational view of a severed section of the rod.

Figure 3 is a plan view showing the curved ends of a severed section of the rod within dies in which they are adapted to be upset, a part of one-half of the right hand die being removed and the position which the cooperating piston occupies when in closed position being indicated in dotted lines.

Figure 4 is a side view of the structure illustrated in Figure 3.

Figure 5 is a view of the rod as it appears after the flattened end portions have been formed thereon by the dies and pistons as shown in Figures 3 and 4.

Figure 6 is an end view of the rod shown in Figure 5.

Figure 7 is a view of one design of a completed grab iron which may be made by suitably bending the rod shown in Figure 5.

Figures 8 and 9 are sectional views taken on lines 8—8 and 9—9, respectively, of Figure 4.

Referring more particularly to the drawings, 1 indicates the rod or bar which is adapted to be formed with a succession of bowed portions 2 by a pair of cooperating die members 3. After being bent by the dies 3 to form a bowed portion 2, the rod is moved in the direction of its length to present the bowed portion to a pair of shearing blades 4 and 5, respectively, the former being movable and the latter being stationary. A suitable support 6 having a semi-circular groove in its upper face is provided adjacent the stationary blade 5 for supporting the rod while it is being cut, the support being of such shape in a direction longitudinally of the rod to conform to a part of the bowed portion.

The movable shearing blade 4 is preferably adapted to move downwardly simultaneously upon each operation of the die members 3 so that each time a new bowed portion is formed in the rod a previously formed bowed portion will be cut at its center. The distance the rod is moved forwardly after each bending and cutting operation may be advantageously limited by an adjustable stop 7 affording an abutment against which the end of the rod is adapted to be brought into engagement.

The bowed portions with which the rod is formed by the dies 3 are of such shape that when they are cut at their mid points by the shearing blades each end of each severed section of the rod will have an identical reverse curve portion 8 and, considering the contour of the flattened portion into which these reverse curve portions are to be forged, the curvature of each of those portions is such that the metal of which they are formed will have to be displaced laterally the least possible distance.

The end portions of each severed section of the rod are placed within dies 9 each of which is preferably formed in two equal parts. Each of the dies has a cavity 10 in which the adjacent reverse curve portion of the rod is arranged. In cross section this cavity is of a shape corresponding to the contour of the feet with which the grab iron is to be formed.

Movable within the cavity of each die in the direction of the axis of the rod for upsetting the reverse curve portion thereof disposed within the cavity is a piston 11 of the same cross sectional shape as the cavity. While one reverse curve portion may be upset and then the other, it is preferred that they be upset simultaneously by having the pistons 11 move toward each other at the same instant.

The front face of each piston is formed with a forwardly extending conical projection 12 which is arranged to engage the adjacent end of the rod in advance of the piston so as to prevent the end from curling over or bending laterally. By thus restraining the ends of the rod from moving transversely of the axis thereof as the reverse curve portions are being upset by inward movement of the pistons, the metal of each reverse curve portion is caused to spread uniformly in opposite directions. In addition to its function of preventing lateral movement of the ends of the rod during upsetting of the reverse curve portions thereof, the conical portions 12 also function to form indentations 13 in the flattened foot portions 14 into which the reverse curve portions are forged. These indentations serve as means for centering a punch or the like which is subsequently employed for producing a hole for receiving a rivet or other securing means in the flattened foot portions. Each rivet hole will thus be properly centered within the foot portion with a uniform amount of material surrounding the hole.

The flattened end portions having the desired contour of the feet of the grab iron which are thus formed in a single upsetting operation of the reverse curve portion are disposed substantially perpendicular to the axis of the rod and it is, of course, necessary to then bend the rod in any preferred manner so as to dispose the flattened portions in the desired relation with respect to the rod to produce the particular design of grab iron required. One of the standard forms of grab irons or handholds which may be easily produced by bending the rod shown in Figure 5 just inwardly of the flattened feet portions is illustrated in Figure 7 of the drawings.

From the foregoing, it will be perceived that a method for forming grab irons has been devised which entails a minimum number of operations and requires but one upsetting operation. It is, of course, to be understood that the method may be practiced by other means than that spe-

cifically illustrated and described without departing from the spirit of the invention as defined in the appended claims.

What I claim is:

1. The method of forming a grab iron having flattened feet for attaching it to a support, which consists in forming a rod with bowed portions at predetermined points intermediate its ends, shearing said rod at the center of said bowed portions whereby each severed section of the rod has reversely curved end portions, upsetting the curved end portions of a severed section of the rod by applying force to the ends thereof in opposite directions parallel with the longitudinal axis of said section to form flattened portions disposed substantially normal to said axis having the contour of the feet of the grab iron, and restraining the ends of said rod from moving transversely of the axis thereof during the upsetting of said curved portions whereby the metal of said portions is spread uniformly in opposite directions; said rod being adapted to be thereafter bent to dispose said flattened portions in the desired relation with respect thereto.
2. The method of forming a grab iron having flattened feet for attaching it to a support, which consists in successively bending intermediate portions of a rod to provide it with spaced bowed portions, moving said rod a predetermined distance in the direction of its length after each bending operation, cutting said rod at the center of each bowed portion whereby the severed sections of the rod respectively have curved end portions, upsetting the curved end portions of a severed section of the rod by applying force to the ends thereof in a direction parallel with the longitudinal axis of said section to form flattened portions arranged substantially normal to said axis having the contour of the feet of the grab iron, and restraining the ends of said rod from moving transversely of the axis thereof during the upsetting of said curved portions whereby the metal of said portions is spread uniformly in opposite directions; said rod being adapted to be thereafter bent to dispose said flattened portions in the desired relation with respect thereto.
3. The method of forming a grab iron having flattened feet for attaching it to a support, which consists in forming a rod with a succession of bowed portions, moving said rod a predetermined distance in a direction of its length after each bowed portion is formed, cutting a previously formed bowed portion at its center simultaneously with the formation of each new bowed portion whereby each severed section of the rod is respectively provided with reversely curved end portions, upsetting the curved end portions of a severed section of the rod by applying force to the ends thereof in opposite directions parallel with the longitudinal axis of said severed section to form flattened portions arranged substantially normal to said axis having the contour of the feet of the grab iron, and restraining the ends of said severed section from moving transversely of the axis thereof during the upsetting of said curved portions whereby the metal of said portions is spread uniformly in opposite directions; said severed section being adapted to be thereafter bent to dispose the flattened portions thereof in the desired relation with respect thereto.

WILLIAM F. CREMEAN.
